SWEDEN

SASH WINDOW AND SASH DOOR

Application filed August 12, 1931, Serial No. 556,650, and in Sweden August 30, 1930.

Sash windows and sash doors have the advantage over doors and windows on hinges that they when open take up less space. Yet they have a drawback, it is not easy to get them tight.

The present invention is a device adapted to be applied to sash doors and sash windows in order to secure complete tightness when the respective door or window is shut.

10 Figure 1 shows a double-window in front view, and

Figure 2 is a horizontal cross section of the same.

Figures 3-8 show details.

15 The frame 1 in which the window is to be located is provided with rebates turned inwards, and it is on one side provided with a slit for letting through the sash window when opening it. The rebates of the frame

20 lie at such a distance from each other that the space between them is larger than the thickness of two window sashes 2. If the sashes 2 are pressed together they may be slid laterally into an intermediate space

25 3 provided in the wall. If the window is to be shut it is slid into the window opening. If the sashes are then separated they are pressed against the respective frame rebates which, if desired, may be provided with

30 tightening lists 4 of rubber, felt or the like.

This separation of the sashes may be effected by a device according to Figure 3. 5 is a disk or pulley provided with two pegs 6 one of which is left- and the other right-

35 handed. The pegs 6 are threaded into nuts 7 disposed on the respective sashes 2. If the disk 5 is turned in one direction and thus also the pegs 6 the sashes approach each other, but if the disk is turned in the other direction

40 they are separated.

On the sashes 2, Figure 1, is located a number of separating devices 8 according to Figure 3. In order to effect a simultaneous turning of the disks 5 a wire or rope 9 is located

45 in a groove in the disks said rope embracing all the disks and in some way or other being secured in the respective disk so that it cannot glide on the same.

If one of the disks 5 is turned the remaining disks are forced by the rope 9 to turn too.

One of the pegs 6 is elongated and provided with a handle 10 in order to effect a turning of the disks 5.

The window may be suspended in the frame in the same way as a common sash window, that is to say it may be suspended in pulleys running on a rail or the like, or it may with or without pulleys stand on the lower portion of the frame, or on an intermediate portion, or it may be suspended by any suitable means.

One frame rebate is formed by a list or board which is removably secured to the frame or the wall by means of screws or suitable mountings. When it is desired to remove the sashes in order to put in a new pane or to clean them, it is only necessary to remove the detachable rebate.

Some details may be carried out in another way without changing the principle. 70 If the invention is to be applied to a part consisting of several window openings space for sliding the slidable sashes may be obtained by disposing the two adjacent sashes forming a stationary double-window at the necessary distance from each other.

Turning of the pegs 6 may also be effected by tie rods secured to the disks 5 or to levers located on the pegs 6, and motion of the rope 9 or of the tie rods mentioned above 80 may also be effected by a handle which does not stand in a direct connection to any separating means, or by means of a slidable handle.

Figure 4 shows a separating device somewhat deviating from the one described above. 85 11 is a disk provided with abutments 12. On the sashes 2 are located plates 13 one of which is provided with a peg 14 running through holes of the disk 11 as well as of the other plate 13, the sashes 2 being thus steadily held in front of each other. The plates 13 are provided with recesses 15 into which the abutments 12 may sink down when the disk 11 is turned to a suitable position. If the disk is turned from this position the sashes are separated. Yet this device is not capable of approaching the sashes, and therefore it is suitable to provide springs between the sashes in order to effect their approaching. 100

These separating means may be manipulated in the same way as the devices according to Figure 3.

Another embodiment consists of the one last described, but so to speak in a reversed manner, that is to say springs are disposed in order to separate the sashes from each other, but this can take place only by substituting an approaching mechanism for the separating mechanism. An advantage offered by this arrangement is also that a vertically slideable window by means of a suitably constructed approaching mechanism can be brought to stop automatically in all vertical positions (for instance if one happens to let loose the handle when manipulating the device).

Figures 6, 7 and 8 show examples of separating devices in the constructions of which the one described above is not included, viz. the rope or wire connecting the separating devices.

Figure 6: 19 is a lever mounted in a pivot 20 and pivotable in the direction shown by the arrow. 21 shows a link which is pivoted to the two sashes for example by means of staples running through holes in the link. The lever 19 is correspondingly secured to one sash. The links 21 may for example be four, one in each corner of the sash pair. If the lever 19 is turned according to the arrow the lever 19 and the links 21 may if the suspension of the sashes is arranged in a suitable manner turn round the geometrical centres 22 whereby the sashes move toward each other.

Figure 7: 23 is a laterally disposed peg secured in one sash. In the other sash is provided a hole to match or a packing box 24. 25 is an eccentric device or crank at the turning of which in one or the other direction the sashes may be slid laterally relatively to each other, and thus the sashes, due to the oblique position of the peg 23, will also move toward and away from each other respectively. The sash pair is preferably provided with a peg and a hole respectively in each corner.

Figure 8 shows an embodiment according to a principle similar to the one shown in Figure 7. The sashes are brought to slide laterally relatively to each other by means of a crank or an eccentric whereby the sashes will move toward and away from each other respectively due to the laterally disposed resting surface along which the sashes abut on each other. Through guides 26 and grooves 27 respectively the sashes are held close to each other during the motion. The bevelling of the mutual resting surfaces of the sashes shown in the figure only occurs at the side portions, and at the upper and lower portions respectively of the sash pair.

The construction shown in Figure 8 may be simplified so as to consist of for instance

four correspondingly bevelled clamp-pairs secured on suitable places to sashes with common section.

The devices described above may be applied also in such a manner that only one sash is imparted a vertical motion toward and away from the plane of the other sash respectively, while the other sash remains unmovable in the said direction. For this purpose the frame portion adjacent to the last-mentioned sash must be made smooth, that is to say without rebate in order to enable the sliding of the sash pair when opening and shutting the window. Said arrangement might facilitate the suspension of the sash pair.

Further the inwardly turned edges of two frame portions may be made without rebate which involves the practical advantage that the motion which the sashes must carry out relatively to each other in order to be slid freely into a recess in a wall or between a pair of adjacent stationary sashes may be reduced to a minimum.

The devices described above may be used in windows adapted to be slid horizontally as well as vertically, and also in doors and the like.

In doors it is unsuitable to use a divided frame bottom portion as one does not wish to have a groove therein. Figure 5 shows a device in which tightening between a door and a plain bottom piece or floor may be produced. 16 is a list the upper surface of which slants laterally inwards. The frames 17 of the door 100 are bevelled to match. When the frames are separated the list 16 is pressed toward the floor or the lower portion 18 of the frame. When the frames 17 are moved toward each other the list 16 may be raised, and thus the door and the list may easily be slid sideways. Raising of the list 16 may suitably be effected by springs disposed between the list and the door frames.

In order to lock a door or window it is enough to lock the handle manipulating the separating means.

The application of the invention to doors and windows with simple frames and sashes respectively may take place in such a way that in the constructions described above one frame and sash respectively is substituted for by a blind frame and blind sash respectively. It is also possible to reduce the blind frame or sash only to an upper and lower portion and the two lateral portions respectively.

Having now described our invention, what we claim as new and desire to secure by Letters Patent is:

1. In windows or doors with double sashes or frames adapted to be slid horizontally or vertically, said frames or sashes being adapted to be slid simultaneously to open or closed condition, the sashes and the frames respectively being adapted to be approached

and separated in order to enable and prevent the sliding respectively, the sashes and the frames respectively being positively governed relatively to each other from a single 5 manipulation point in order to approach or separate said frames and sashes respectively, and thus the window or door respectively is opened.

2. In windows or doors with double sashes 10 or frames adapted to be slid horizontally or vertically, said frames or sashes being adapted to be slid simultaneously to open or closed condition, the sashes and the frames respectively being adapted to be approached 15 and separated in order to enable and prevent the sliding respectively, the sashes and the frames respectively being positively governed relatively to each other from a single manipulation point in order to approach or separate 20 said frames and sashes respectively, and thus the window or door respectively is closed.

3. In windows or doors with double sashes 25 or frames adapted to be slid horizontally or vertically, said frames or sashes being adapted to be slid simultaneously to open or closed condition, the sashes and the frames respectively being adapted to be approached and separated in order to enable and prevent 30 the sliding respectively, the sashes and the frames respectively being positively governed relatively to each other from a single manipulation point in order to approach or separate 35 said frames and sashes respectively, and thus the window or door respectively is brought to tighten against the frame in any position.

4. Device according to claim 1 in which the sashes and the frame respectively only by the positive approaching motion are adapted to 40 produce a parallel running slot round the sashes for the purpose of air exchange thus without entirely sliding the window or door after approaching the sashes.

5. In windows or doors with double sashes 45 or frames adapted to be slid horizontally or vertically, said frames or sashes being adapted to be slid simultaneously to open or closed condition, guides cooperating with said sashes for positioning the sashes in the 50 opening to be closed thereby, means for moving the sashes together and away from each other to enable sliding of the sashes and prevent sliding of the sashes by effecting binding contact between the sashes and the guides, 55 respectively.

6. In windows or doors with double sashes or frames adapted to be slid horizontally or vertically, said frames or sashes being adapted to be slid simultaneously to open 60 or closed condition, means cooperating with said sashes for effecting a tight joint between the sashes and the edges of the opening to be closed by the sashes, means for forcing the sashes apart to prevent sliding of the sashes 65 relative to the cooperating means and to effect

a tight joint between the sashes and the cooperating means.

7. In windows or doors with double sashes or frames adapted to be slid horizontally or vertically, said frames or sashes being 70 adapted to be slid simultaneously to open or closed condition, means cooperating with said sashes for effecting a tight joint between the sashes and the edges of the opening to be closed by the sashes, cam means for forcing the sashes apart to prevent sliding of the sashes relative to the cooperating means and to effect a tight joint between the sashes and the cooperating means.

8. In windows or doors with double sashes or frames adapted to be slid horizontally or vertically, said frames, or sashes being adapted to be slid simultaneously to open or closed condition, guides cooperating with 80 said sashes for positioning the sashes in the opening to be closed thereby, link means for moving the sashes together and away from each other to enable sliding of the sashes and prevent sliding of the sashes by effecting binding contact between the sashes and the 85 guides, respectively.
